2,143,455

PROCESS OF VULCANIZING RUBBER AND
PRODUCTS OBTAINED THEREBYRobert L. Sibley, Nitro, W. Va., assignor, by mesne
assignments, to Mensanto Chemical Company,
St. Louis, Mo., a corporation of DelawareNo Drawing. Application October 23, 1930,
Serial No. 490,814

5 Claims. (Cl. 18—53)

This invention relates to the vulcanization of
rubber by an improved process, wherein there is
employed a member of a preferred class of com-
pounds and Table II gives the results when
diphenylguanidine benzoate is so used.

Table I

Time of cure	No. parts diphenyl- guanidine hydrochloride	Modulus of elasticity in lbs./in. ² at elongations of—			Tensile lbs./in. ² at break	Ultimate elongation, percent

employed a member of a preferred class of compounds which improve the action of the accelerator used in the vulcanization process and with them form a mixed accelerator. The preferred class of compounds employed in the manner hereinafter described comprises salts of a guanidine and derivatives thereof.

As examples showing the use of the preferred class of compounds, a rubber mix was prepared in the well known manner comprising 100 parts of pale crepe rubber, 5 parts of zinc oxide, 3 parts of sulfur, 0.5 part of the crotonaldehyde derivative of the reaction product of mercapto-benzothiazole and hexamethylene-tetramine, 0.5 part of diphenylguanidine, and 0.1 and/or 0.2 part of a compound of the preferred class of activators as hereinafter mentioned. The mix was then vulcanized by heating under various pressures and for various periods of time. The cured stock was then tested to determine its modulus and tensile strength under various degrees of elongation. The results of the tests of the rubber composition thus described are set forth in the following tables. Table I gives the results when diphenylguanidine hydrochloride is employed as an example of the preferred class

It is readily apparent from the data set forth in Tables I and II that the preferred class of materials possesses highly desirable activation properties.

As examples of the use of the preferred class of compounds, showing retarding effect in the shorter timed and lower steam pressure cures and activation in the longer timed and higher steam pressure cures, the following three rubber stocks, designated "A", "B" and "C" were prepared and tested in the manner hereinbefore set forth.

	Stock A	Stock B	Stock C
Pale crepe rubber	Parts 100	Parts 100	Parts 100
Zinc oxide	8	8	8
Sulfur	2.5	2.5	2.5
Stearic acid	0.5	0.5	0.5
Crotonaldehyde derivative of the reaction product of mercapto-benzothiazole and hexamethylene-tetramine	0.4	0.4	0.4
Diphenylguanidine	0.6		
Diphenylguanidine phthalate		0.6	
Diphenylguanidine acetate			0.6

The results of the tests upon the above described rubber stocks after curing for various periods of time and under various steam pressures are given in Table III, which shows by comparison the

desirable effect of the presence of a compound of the preferred class, as for example diphenylguanidine phthalate and diphenylguanidine acetate, on the cure of a rubber stock of vulcanization characteristics.

comprising 100 parts of pale crepe rubber, 5 parts of zinc oxide, 3 parts of sulfur, 1 part of stearic acid, 0.4 part of the acetaldehyde derivative of the reaction product of para-para-diamino-diphenyl-methane and mercaptobenzothiazole, and 5

45 A comparison of the results given in Table III shows that the preferred class of materials as for example diphenylguanidine phthalate and diphenylguanidine acetate, not only activate the curing process in the longer timed and higher steam pressure cures, but also greatly retard the cure in the shorter timed and lower steam pressure cures. This retardation of cure at the lower temperatures is a highly desirable property, as scorching or vulcanizing on the mixing rolls is thereby substantially prevented.

50

55 As further examples of the use of the preferred class of materials, a rubber mix was prepared

0.6 part of the preferred class of materials. The results of the tests upon the above rubber stock 45 after curing are given in the following tables. Table IV gives the results of tests of the cured rubber product in which diphenylguanidine phthalate was incorporated in the above described rubber stock prior to the vulcanization thereof. Table 50 V gives the results of tests obtained when diphenylguanidine hydrochloride was employed in the manner described above, and Table VI sets forth the results obtained when diphenylguanidine acetate was employed in the above identified stocks 55 in the manner described.

5 A stock identical with that employed in the test given in Tables IV, V and VI with the exception

20 The results of the tests upon the above rubber stock after curing are given in Table VII.

35

Table VII

40	Time of cure	Modulus of elasticity in lbs/in. ² at elongations of—			Tensile lbs/in. ² at break	Ultimate elongation, percent	40
		300%	500%	700%			
45	20 minutes at 10# steam per square inch	—	—	—	Did not cure	—	45
	30 minutes at 10# steam per square inch	290	890	2350	2955	790	
	10 minutes at 20# steam per square inch	200	578	1550	2285	825	
	15 minutes at 20# steam per square inch	301	925	2470	2865	750	
	30 minutes at 20# steam per square inch	361	1140	2960	3500	760	
	45 minutes at 20# steam per square inch	404	1250	3185	3595	735	
	60 minutes at 20# steam per square inch	434	1280	3360	3515	720	

50 that diphenylguanidine was substituted for the diphenylguanidine salts, on curing for 20 minutes at 10# steam pressure, gave a tensile at break of 2780 lbs./in.² and an ultimate elongation of 920%.
55 The foregoing tests given in Tables IV, V and VI show that the preferred class of activating materials, when employed in the rubber stock described, retards or delays the curing action during the early stages of the vulcanization process but permits the accelerator to exert substantially its normal effect at full cure. In fact, the materials appear to first serve as retarders and later as activators, at least, the full activating effect of the materials is not produced during the early stages of the cure.

60 As a further example of the use of the preferred class of materials, a rubber stock was prepared comprising the following:

	Parts
Pale crepe rubber	100
Sulfur	2
Zinc oxide	5
Whiting	30
Lithopone	20
Palm oil	2
The reaction product of 2 mols mercaptobenzothiazole and 1 mol phthalyl chloride	.6
Diphenylguanidine	.1
Diphenylguanidine phthalate	.399

50 It is readily apparent from the results set forth in Table VII that in the presence of one of the preferred class of materials, for example, diphenylguanidine phthalate, the vulcanization is retarded in the early period of the cures, but this retarding effect is not continued in the longer cures and the cures at the higher steam pressures.

55 As a further example of the use of the preferred class of materials, a rubber stock was prepared comprising the following:

Parts
100
2
5
30
20
2
.492
.0818
.3262

60 The results of the tests upon the above rubber stock after curing are given in Table VIII.

75

Table VIII

5	Time of cure	Modulus of elasticity in lbs/in. ² at elongations of—			Tensile lbs/in. ² at break	Ultimate elongation, percent	5
		300%	500%	700%			
10	20 minutes at 10# steam per square inch				Did not cure		
	30 minutes at 10# steam per square inch	177	496	1,315	1850	805	
	10 minutes at 20# steam per square inch	215	665	1,850	2,450	800	10
	15 minutes at 20# steam per square inch	306	960	2,600	3,360	780	
	45 minutes at 20# steam per square inch	374	1,155	3,050	3,420	750	
	60 minutes at 20# steam per square inch	412	1,265	3,185	3,340	730	

15 It is apparent from the results set forth in Table VIII that in this example also, as in previous examples cited, the presence of one of the preferred class of materials, for example, diphenylguanidine phthalate, retards the vulcanization process in the shorter timed cures, but the vulcanization of the compounded rubber stock wherein the preferred class of materials is incorporated is not retarded on the longer heating period and at the higher steam pressure cures.

The results of the tests upon the above rubber stocks after curing are given in Table IX.

Table IX

20	Cure, minutes	Steam pressure in lbs/in. ²	Stock	Modulus of lbs/in. ² at 300%	Elasticity in elongations of 500%	Tensile lbs/in. ² at break	Ultimate elongation, percent	20
25	30	10	A B	322 325	1108 880	1553 939	590 520	25
	40	10	A B	530 500	1568 1298	2370 1850	630 620	
30	60	10	A B	871 727	2280 1845	3440 2393	630 570	30
	20	20	A B	587 452	1698 1250	2280 1960	575 650	
	30	20	A B	880 748	2270 1970	3395 2680	635 600	
35	45	20	A B	1195 1003	2890 2480	4490 3610	670 625	35
	60	20	A B	1488 1345	3445 3020	4930 4320	625 620	
40	90	20	A B	1650 1650	3685 3605	4860 4905	610 610	40
	120	20	A B	1890 1660	4100 3725	4860 4725	570 590	

45 previous examples cited, the presence of one of the preferred class of materials, for example, diphenylguanidine phthalate, retards the vulcanization process in the shorter timed cures, but the vulcanization of the compounded rubber stock wherein the preferred class of materials is incorporated is not retarded on the longer heating period and at the higher steam pressure cures.

50 As further examples of the use of the preferred class of materials, two rubber stocks, designated "A" and "B", were prepared and tested for comparison, stock "A" comprising diphenylguanidine as an activator and stock "B" comprising diphenylguanidine acetate in its stead as one of the preferred class of materials. The rubber stocks here referred to comprised the following ingredients:

65		Stock A	Stock B
70	Smoked sheet rubber	Parts	Parts
	Carbon black	100	100
	Zinc oxide	40	40
	Sulfur	5	5
	A blended mineral and vegetable oil	3	3
	Stearic acid	2	2
	Acetaldehyde derivative of the reaction product of para-para-diamino diphenylmethane and mercaptobenzothiazole	1	1
	Diphenylguanidine	0.36	0.36
	Diphenylguanidine acetate	0.84	0.84

45 A comparison of the results given in Table IX gives further proof that the presence of one of the preferred class of materials, for example, diphenylguanidine acetate, retards the vulcanization in the shorter timed and lower steam pressure cures, but activates the vulcanization in the longer timed and higher steam pressure cures.

50 The results hereinbefore set forth show that a vulcanized rubber product of particularly high quality is obtained by employing the preferred substances in a rubber stock, of vulcanizing characteristics.

55 Other salts of guanidines than those hereinbefore set forth may be employed in the manner described. Thus, the phthalate, hydrochloride, acetate, and similar salts of di-ortho-tolyl-guanidine, dixylylguanidines, triphenylguanidines, and analogous compounds may be employed in the vulcanization of rubber in a manner analogous to that hereinbefore set forth.

60 This invention is not restricted to the use of the particular compounds given in the disclosure as examples, nor is it restricted to the use of the preferred class of compounds in the particular rubber mixes herein described. The invention is limited only by the claims attached hereto as part of the present specification.

65 What is claimed is:

70 1. The process of vulcanizing rubber which comprises heating a mixture of rubber and sulfur in the presence of diphenylguanidine phthalate

and in addition thereto a mercaptothiazole accelerator.

2. The process of vulcanizing rubber which comprises heating a mixture of rubber and sulfur in the presence of an accelerator containing di-
5 phenylguanidine phthalate and a reaction product of substantially two molecular proportions of mercaptobenzothiazole and substantially one molecular proportion of phthalyl chloride.

10 3. The process of vulcanizing rubber which comprises heating rubber and sulphur in the presence of a mercapto aryl thiazole accelerator and the diphenyl guanidine neutral salt of phthalic acid.

15 4. The process of initially retarding the ac-

celerating action of a mercaptothiazole accelerator and later activating the accelerating action thereof which comprises heating rubber and sulphur in the presence of a mercaptothiazole accelerator and the diphenyl guanidine neutral salt 5 of phthalic acid.

5. The process of vulcanizing rubber which comprises heating a mixture of rubber and sulfur in the presence of a thiazyl sulphide accelerator and in addition thereto an aryl substituted guanidine salt of an aromatic carboxylic acid, said acid being one of a group consisting of phthalic 10 and benzoic acids.

ROBERT L. SIBLEY. 15
